UNITED STATES PATENT OFFICE.

LEE STURGES, OF ELMHURST, ILLINOIS.

DESIGN FOR A SPROCKET-WHEEL AND CHAIN GUARD.

SPECIFICATION forming part of Design No. 27,921, dated November 30, 1897.

Application filed June 12, 1897. Serial No. 640,586. Term of patent 7 years.

To all whom it may concern:

Be it known that I, LEE STURGES, of Elmhurst, in the county of Du Page and State of Illinois, have invented a certain new and original Design for Sprocket - Wheel and Chain Guards for Bicycles, of which the following is a specification.

The essential feature of my design consists in the peculiar shape or configuration of the chain-guard provided with the open-work, which occupies the interior of the guard, as shown in Figure 1, which is a perspective view of a guard embodying my novel design. Fig. 2 is a transverse sectional detail taken on line 2 2 of Fig. 1.

The exterior rim of the guard is of the usual shape and its upper and lower rails A' are connected by three upright bars a, a', and a'', shaped as shown. The upright a' co-
operates with the exterior rim to form a circular opening at the larger end of the guard and the upright a'' co-operates in a similar manner with the smaller end of the guard to form an oval space C. Between these two

end spaces the upright a'' separates two other spaces D and E, of which the one nearer the smaller end of the guard is circular, while the other one is of the shape substantially of a flattened vertically-arranged ellipse. The configuration thus described is heightened in effect by small substantially triangular openings F, formed at the juncture of the vertical bars with the upper and lower rails of the guard. An outwardly-rounded bead A'' is shown as extending along the rails and around the ends of the guard.

Having thus described my invention, what I claim is—

The design for a chain and sprocket-wheel guard, substantially as shown and described. 40

In testimony that I claim the foregoing as my invention I affix my signature, in presence of two subscribing witnesses, this 8th day of June, A. D. 1897.

LEE STURGES.
